2 SHEETS—SHEET 2.

UNITED STATES PATENT OFFICE.

JACOB W. LATTIG, OF GLENSIDE, PENNSYLVANIA, AND CHARLES L. GOODRUM, OF NEW YORK, N. Y., ASSIGNEES, BY MESNE ASSIGNMENTS, TO WESTERN ELECTRIC COMPANY, INCORPORATED, A CORPORATION OF NEW YORK.

METERING SYSTEM FOR AUTOMATIC TELEPHONE-EXCHANGES.

1,264,402.

Specification of Letters Patent. Patented Apr. 30, 1918.

Application filed September 24, 1915. Serial No. 52,511.

To all whom it may concern:

Be it known that we, JACOB W. LATTIG and CHARLES L. GOODRUM, citizens of the United States, residing at Glenside, in the 5 county of Montgomery and State of Pennsylvania, and at New York, in the county of New York and State of New York, respectively, have invented certain new and useful Improvements in Metering Systems for 10 Automatic Telephone-Exchanges, of which the following is a full, clear, concise, and exact description.

This invention relates to telephone systems and more particularly to metering systems 15 for automatic telephone exchanges.

The object of this invention is to provide a metering system for telephone exchanges, in which the subscribers are charged for the originated calls in accordance with the services rendered.

According to one feature of this invention, the calling subscriber is charged for the time while he occupies a trunk line, and the rate of charge is made dependent upon 25 the trunk in use. If the call is established through a certain trunk, the charge is made according to a predetermined rate, and if the call is extended through another, a more expensive trunk, the charge is made at a 30 higher rate.

According to another feature of this invention, the calling subscriber is charged for the time while he employs a certain trunk for conversation with a called subscriber, the rate of this charge being preferably higher than that made for the use 35 of the same trunk in the establishment of a connection. If the conversation is carried on through a more expensive trunk, a 40 higher rate is charged.

Still another feature of this invention calls for a system in which the called subscriber is charged for the time while a trunk is employed for conversation, if a "reverse-charge" subscriber's line is called. By a 45 "reverse-charge" subscriber is meant one, calls to whom are not to be charged against the calling but against the called subscriber.

The invention will be more fully understood from the following detailed description of the system and the drawings in which Figures 1 and 2 taken together, show diagrammatically a telephone system embodying the present invention; and Fig. 3

placed to the right of Fig. 1, represents a 55 telephone system embodying those features of this invention which relate to the "reverse-charge" service.

As the automatic switches employed in the building up of a connection form no 60 part of this invention, their structure and detail circuit arrangement will not be shown. The operation of such switches is well-known in the art and a description of the same may be had from British Patent 65 to applicants No. 16,479-A, August 14, 1905.

This invention may be readily adapted for use in connection with systems of widely varying character in which switches are employed for the building up of a connection by means of current impulses originated at the calling subscriber's station, or at an operator's position.

Subscriber 1 desiring to initiate a call removes his receiver from the switch hook and trunk finder 2 is started to hunt for an idle trunk leading to a selector switch 3. When trunk finder 2 reaches with its wipers 4, 5, 6 and 7, the terminals 10, 11, 12 and 13 of such a trunk, the trunk finder is arrested 80 and the selected trunk is rendered busy in the well-known manner. Subscriber 1 sends now, by means of his impulse sender 14, the first set of impulses representing the number of the called subscriber 8. By means of 85 these impulses, selector switch 3 is set onto the terminal of a trunk leading to the office in which the called subscriber 8 is located, and if the trunk is idle, selector 3 is arrested with its wipers on the terminals of this 90 trunk and the trunk is rendered inaccessible to other incoming calls. During the sending out of impulses *i. e.*, the intermittent grounding of the upper and lower limbs of the connecting circuit (indicated in heavy 95 lines) current flows from a common central battery through one of these limbs to ground at the substation 1.

Supposing that trunk line 15, 16, 17 was selected, and wipers 20, 21, 22, 23, 24 of 100 selector 3 are arrested on terminals 25, 26, 27, 28, 29 of the selected trunk, a circuit is closed from ground through interrupter 30, terminal 29 and wiper 24 of selector 3, armature and back contact of polarized relay 31, back contact and armature of polarized relay 32, terminal 10 and wiper 4 of trunk finder 2, winding of polarized meter 105

magnet 33, to grounded battery 34. Under the control of the interrupter 30, meter magnet 33 causes, by means of a train of wheels, a registering device of any well-known design to advance as long as relays 31 and 32 remain deenergized. Normally, the current flowing in the connecting circuit in which relays 31 and 32 are included is not of the proper polarity to energize these relays, and therefore, during the building up of the connection, those relays will remain deenergized. Should selector switch 3 be set on a trunk which terminates in the third row of stationary contacts of its terminal bank instead of interrupter 30, interrupter 35 would be connected in circuit with the meter magnet 33 to cause said meter magnet to operate faster in order to cause the registration of the charge at a higher rate for the use of this trunk than the charge was for the use of trunks 15, 16, 17.

The calling subscriber proceeds now to send out the second and third set of impulses for the setting of selector switch 36 and connector 37 located at the distant exchange. Preferably these impulses are repeated to switches 36 and 37 by means of relays or other well-known repeating means. After selector 36 and connector 37 have been set, the two limbs of the connecting circuit are supplied with current from grounded battery 40, through the outer armature and back contacts of relay 41 and resistances 42 and 43. The called subscriber's line is supplied with current from grounded battery 44, through the winding of relay 41, resistance 45, lower limb of the connecting circuit, station of subscriber 8, upper limb of the connecting circuit and resistance 46 to ground. When the called subscriber in response to the ringing current applied to his line, removes his receiver from the switchhook, relay 41 becomes energized and by attracting its armature reverses the direction of the current flowing in the upper limb of the talking circuit and causes thereby the energization of polarized relay 32, which, by attracting its armature opens the circuit, connecting interrupter 30 with meter magnet 33 and closes through its front contact a circuit from grounded battery 34, through the winding of polarized meter magnet 33, wiper 4 and terminal 10 of switch 2, armature and front contact of polarized relay 32, wiper 20 and terminal 25 of selector 3 and interrupter 47 to ground. As long as relay 32 is energized, that is, as long as the calling and called subscribers are engaged in conversation, meter magnet 33 causes the registering device to record the time or the amount due for the time, under the control of interrupter 47.

Should a trunk terminating for instance, 65 in the third row of terminals of selector

switch 3 be selected, instead of interrupter 47, upon the answering of the called line, interrupter 48 would be connected in circuit with the meter magnet 33 and would cause the recording of a charge at a higher rate than in the previously mentioned case. Interrupters 47 and 48 are preferably of a higher speed than interrupters 30 and 35, and therefore the charge made for the time while a trunk line is occupied for the building up of connection is lower than the charge made for the time while the trunk is used for conversation.

If the selector 3 is set on the row of contacts in which trunks individual to "reverse-charge" lines terminate, during the building up of the connection, the calling subscriber's meter magnet 33 is operated in the same manner as above described. After switches 53 and 54 have been set by the calling subscriber to select the line of a "reverse-charge" subscriber 55, and the called subscriber removes his receiver, relay 56 becomes energized. Normally, grounded battery 57 is connected to the two limbs of the connecting circuit through the outer armature and back contacts of relay 56 and resistances 58 and 59. The current flowing through the lower limb of the connecting circuit is not of the proper polarity to energize relays 31 and 32. Upon the energization of relay 56 this battery connection is reversed in the lower limb of the connecting circuit, grounded battery 57 being connected to the upper and ground to the lower limb of the connecting circuit. Polarized relay 32 remains deenergized, but polarized relays 31 and polarized relay 69 become energized. Relay 31 opens the circuit between interrupter 30 and meter magnet 33, stopping thereby the meter in its operation. Polarized relay 69 by attracting its armature, closes a circuit from ground through interrupter 61, its armature and front contact, wiper 62 of selector 53, a conductor 63, wiper 64 of connector 54, conductor 65, windings of meter magnet 66 to grounded battery 67. The meter magnet of the called subscriber causes, under the control of interrupter 61, the registration of the time while the calling and called subscribers are engaged in conversation. As polarized relay 32 has not been energized, the calling subscriber's meter does not operate during the conversation.

Interrupters 30, 35, 47 and 48 are preferably mounted on a constantly rotating common shaft.

What is claimed is:

1. In a telephone system, a plurality of 125 lines, means for establishing a connection between a calling and a called line, call charging means individual to a line, and means for operating the same during the building up of said connection.

2. In a telephone system, a plurality of lines, automatic switches for establishing a connection between a calling and a called line, call charging means individual to a line, and means for actuating the same during the operation of said automatic switches.
3. In a telephone system, a plurality of lines, selector switches for establishing a connection between a calling and a called line, a call register individual to a line, and means for operating the same upon the setting of one of said switches, said register being operated during the operation of the other switches.
4. In a telephone system, a plurality of lines, selector switches for establishing a connecting circuit between a calling and a called line, a call register, an interrupting device, a polarized relay included in said connecting circuit, and having normally closed contacts, means controlled by one of said switches for connecting said interrupting device to said register through said contacts of the polarized relay, and means controlled by the called line for changing the current flowing in said connecting circuit for causing said polarized relay to open said contacts.
5. In a telephone system, a plurality of lines, a plurality of trunks, automatic switches for establishing a connection between a calling and a called line through any one of said trunks, a call register, means for operating said call register at one rate during the operation of said switches, if the connection is established through a certain trunk, and means for operating said call register at another rate, during the operation of said switches, if the connection is established through another trunk.
6. In a telephone system, a plurality of lines, a plurality of trunks, automatic switches for establishing a connection between a calling and a called line through any one of said trunks, a call register, means for operating said call register at a low rate during the operation of said switches, if the connection is established through a certain trunk, and means for operating said call register at a higher rate during the operation of said switches, if the connection is established through another trunk.
7. In a telephone system, a plurality of lines, selector switches for establishing a connecting circuit between a calling and a called line, a call register, interrupting devices, a polarized relay included in said connecting circuit and having normally closed and normally open contacts, means controlled by one of said switches to connect one of said interrupting devices to said register through the normally closed contacts of said relay, means controlled by the called line to change the flow of current in said connecting circuit for causing said relay to actuate said contacts and means including said polarized relay operative thereupon for connecting another of said interrupting devices to said register.
8. In a telephone system, a plurality of lines, automatic switches for building up a connection between a calling and a called line, call charging means, means for operating the same during the operation of said switches, and means for causing said call charging means to operate after the complete establishment of said connection.
9. In a telephone system, a plurality of lines, automatic switches for establishing a connection between a calling and a called line, a call register, means for operating the same during the operation of said switches, and means controlled by the called line for operating said call register after the complete establishment of said connection.
10. In a telephone system, a plurality of lines, a plurality of trunks, automatic switches for establishing a connection between a calling and a called line through any one of said trunks, means for operating said call register during the operation of said switches, means for operating said call register after the completion of the connection at one rate if the connection was established through a certain number of trunks, and means for operating said call register after the completion of the connection at another rate if the connection was established through another number of trunks.
11. In a telephone system, a plurality of lines, a plurality of trunks, automatic switches for establishing a connection between a calling and a called line through any one of said trunks, means for operating said call register at a low rate during and after the building up of said connection if the connection is established through a certain number of trunks, and means for operating said call register at a higher rate during and after the building up of the connection if the connection is established through another number of trunks.
12. In a telephone system, a plurality of lines, reverse-charge lines, automatic switches for establishing a connection between a calling and a called line, a call register for each of said lines, means for actuating the call register of the calling line during the operation of said switches, means for operating the call register of said line after the complete establishment of said connection, and means for preventing said second operation of the register if the called line is a reverse-charge line.
13. In a telephone system, a plurality of lines, a plurality of reverse-charge lines, automatic switches for establishing a connection between a calling and a called line, a call register for each of said lines, means for operating the register of the calling line during the operation of said switches, means for actuating the call register of said line after the complete establishment of said connection, and means for preventing said second operation of the register if the called line is a reverse-charge line.

ing the operation of said switches, means operative upon the complete establishment of a connection with a reverse charge called line for preventing the operation of the register of the calling line, and means operated simultaneously with the last mentioned means for causing the operation of the register of the called line.

14. In a telephone system, a plurality of lines, reverse-charge lines, automatic switches for establishing a connection between a calling and a called line, a call register for each of said lines, a polarized relay having normally closed and normally open contacts, means controlled by one of said switches to operate said register through said closed contacts, during the operation of the other switches, means controlled by the called line for causing said relay to actuate its contacts, means for operating said register through the actuated contacts after the complete establishment of said connection, and means for preventing the second operation of the register if the called line is a reverse-charge line.

15. In a telephone system, a plurality of lines, a plurality of reverse-charge lines, automatic switches for establishing a connecting circuit between a calling and a called line, a call register for each of said lines, means for operating the register of the call-

ing line during the operation of said switches, a plurality of normally deenergized polarized relays included in series in said connecting circuit, means operative upon the establishment of a connection with a reverse-charge line for energizing said relays, means controlled by one of said relays to prevent the operation of the register of the calling line, and means controlled by another of said relays for causing the operation of the register individual to the called line.

16. In a telephone system, a plurality of lines, a plurality of trunks, automatic switches for establishing a connection between a calling and a called line, a call register, two groups of interrupting devices, two polarized relays for connecting an interrupting device of one group to said call register, and means for reversing the flow of current through one of said relays to cause the connection of an interrupting device of the other group of said call register.

In witness whereof, I hereunto subscribe my name this ninth day of Sept., A. D., 1915.

JACOB W. LATTIG.

Witness:

CHARLES COMLY.

In witness whereof, I hereunto subscribe my name this seventeenth day of September, A. D., 1915.

CHARLES L. GOODRUM.
